UNITED STATES PATENT OFFICE.

ELBERT C. LEACH, OF OSHKOSH, WISCONSIN, ASSIGNOR TO LEACH COMPANY, OF OSHKOSH, WISCONSIN, A CORPORATION OF WISCONSIN.

MIXER-DRUM CONSTRUCTION.

Application filed July 8, 1926. Serial No. 121,978.

This invention has to do with mixer drums, such as are used extensively in mixing concrete and other generally similar materials.

5 The principal object of the invention is to provide an improved mixer drum in which the heads are so formed and connected as to produce a structure which is light, strong and durable, is extremely inexpensive and 10 simple to manufacture, and will operate on concrete and other materials in a very efficient manner.

Other objects and advantages will be apparent to those skilled in the art upon a 15 full understanding of the nature of the drum construction.

One form of the invention is presented herein for the purpose of exemplification, but it will, of course, be understood that the 20 invention is susceptible of embodiment in other slightly modified forms coming equally within the comprehensive scope of the appended claim.

In the accompanying drawing:

25 Fig. 1 is a partly sectioned side view of a drum constructed in accordance with the invention;

Fig. 2 is an end view of the drum; and

30 Fig. 3 is an enlarged radial section through one of the heads of the drum.

The drum illustrated in the drawing is a sheet metal structure formed in three sections 10, 11 and 12. The intermediate section 10 is a plain sheet metal cylinder, while 35 the two head sections 11 and 12 are dished sheet metal disks of S-shaped radial section.

Each of the heads 11 and 12 is provided with a central aperture 13—which is the charging opening in the head 11 and the 40 discharging opening in the head 12—and, commencing from the edge of the aperture, extends radially a short distance at 14, then slopes toward the inside of the drum at 15, then slopes away from the inside at 16, and 45 then curves back toward the inside at 17 and terminates in a cylindrical edge which telescopes within and is lap-welded to the adjacent edge of the cylinder 10 at 18.

The radial portion 14 is more removed 50 from the inside of the drum than the slop-

ing and curved portions 15, 16 and 17, and is provided with a ring 19 which is welded to the same where the portions 14 and 15 merge. The ring 19 forms a short continuation of the portion 14, and causes any concrete which may spill out of the aperture 13 to drip clear of the drum instead of spreading and accumulating on the outside face of the portions 15, 16 and 17 of the drum, as would be the case were the drip ring not used.

The inwardly sloping portion 15 provides a passageway which is of increasing width toward the mixing chamber, whereby to deflect any concrete contacting therewith into the mixing chamber, and the oppositely sloping portion 16 gives a concave shape to the drum end, whereby to cause concrete coming into contact therewith to be deflected back into the center of the mixing chamber.

The drum is provided, interiorly of the same, with a number of mixing blades 20, and, exteriorly of the same, with a band gear 21, the blades 20 and the gear 21 being secured to opposite sides of the cylinder 10. As will be observed, the gear 21 is flanged laterally in order to provide an extended cylindrical support for the cylinder 10. The aperture 13 in the head 12, being the discharge opening in the drum, is preferably smaller than the corresponding aperture in the head 11, and the portion 14 of the head 12 is consequently of proportionately greater radial extent.

I claim:

In a mixer drum, a head in the form of a single apertured sheet metal disk which is shaped in such a way that the portion of the disk immediately surrounding the aperture lies in one plane and is located farther from the inside of the drum than the other portions of the disk, and a drip ring of greater circumference than the portion of the disk about the aperture, which ring is welded to said portion in radial continuity with the same.

In testimony whereof I have hereunto subscribed my name.

ELBERT C. LEACH.
